TOILET SEAT COVER

Kerry A. Day, Parsippany, N.J., assignor to American Standard Inc., New York, N.Y.

Filed July 10, 1972, Ser. No. 270,100

Term of patent 14 years

Int. Cl. D23—02

U.S. Cl. D23—71

FIG. 1

FIG. 3

FIG. 2

FIG. 1 illustrates a top plan view of the toilet seat cover of this invention embodying my new design;

FIG. 2 is a bottom plan view thereof; and
FIG. 3 is a side elevational view thereof.

I claim:

The ornamental design for a toilet seat cover, substantially as shown.
